[57] CLAIM

The ornamental design for a security system control panel, as shown and described.

DESCRIPTION

FIG. 1 is a perspective view of the security system control panel showing my new design;

FIG. 2 is a front elevational view of the control panel;

FIG. 3 is a front elevational view of the control panel displaying all possible outputs on the control and display pad;

FIG. 4 is a side elevational view of the control panel (taken from the right side);

FIG. 5 is a front elevational view of the control panel showing an extended instruction sheet page; and,

FIG. 6 is a side elevational view of the control panel showing an extended instruction sheet page.

The broken lines are shown for illustrative purposes only and form no part of the claimed design.
